UNITED STATES PATENT OFFICE

143,715

DESIGN FOR A BABY BATH

Peyton W. Douglas, Syracuse, N. Y.

Application January 15, 1945, Serial No. 117,442

Term of patent 14 years

(Cl. D4—4)

To all whom it may concern:

Be it known that I, Peyton W. Douglas, a citizen of the United States of America, and resident of Syracuse, in the county of Onondaga and State of New York, have invented a new, original, and ornamental Design for a Baby Bath, of which the following is a specification, reference being had to the accompanying drawing forming part thereof.

In the drawing:

Figure 1 is a perspective view of a baby bath showing my design, opened in position for use in

bathing a baby, and showing the towel rack in extended position, ready for use;

Figure 2 is a perspective view similar to Figure 1, but showing the cover lowered to form a table for dressing the baby, and showing the towel bar retracted; and

Figure 3 is a perspective view showing the baby bath in completely closed position.

I claim:

The ornamental design for a baby bath, substantially as shown and described.

PEYTON W. DOUGLAS.
